UNITED STATES PATENT OFFICE.

FRANCIS W. DRAPER, OF DETROIT, MICHIGAN, ASSIGNOR TO FARRAND ORGAN COMPANY, OF DETROIT, MICHIGAN, A CORPORATION OF MICHIGAN.

AUTOMATIC PRESSURE-REGULATOR FOR PNEUMATIC ACTIONS OF MUSICAL INSTRUMENTS.

No. 892,033.

Specification of Letters Patent.

Patented June 30, 1908.

Application filed April 3, 1905. Serial No. 253,546.

To all whom it may concern:

Be it known that I, FRANCIS W. DRAPER, residing at Detroit, in the county of Wayne and State of Michigan, a citizen of the United States, have invented certain new and useful Improvements in Automatic Pressure-Regulators for Pneumatic Actions of Musical Instruments, of which the following is a specification, reference being had therein to the accompanying drawings.

The invention relates to pressure regulators, more especially designed for use in pneumatic actions for automatic musical instruments, and the invention consists in the novel construction as hereinafter set forth.

In the drawings, Figure 1 is a longitudinal section through the regulator. Fig. 2 is a plan view of a portion thereof, showing the adjustable valves.

In the construction of auto-pneumatic musical instruments, it is usual to provide in addition to the regulating store bellows, independent means for regulating the pressure of air used in different parts of the instrument, as for instance the air employed for operating the motor. The present invention relates to the peculiar construction of a regulator for this purpose; and an important feature of the construction is the means by which the regulator will be adjusted to operate uniformly in different positions of adjustment of the tempo valve.

As shown, A is a casing or box, within which is arranged the tempo valve B, slidably secured in guides C and controlling the port D. This port connects with a channel E, leading through the walls of the casing and communicating with a chamber F therein.

G is a cylinder which is open at opposite ends, and one end of which communicates with the chamber F, and the opposite end with a second chamber H also within the casing. Intermediate the ends of the cylinder are ports I, arranged in circular series and communicating with a passage J formed in the walls of the chest intermediate the chambers F and H. This passage J leads to the store bellows or other source of pneumatic pressure.

K is a piston slidable within the cylinder G, which is preferably cup-shaped in form.

L is a spring, the free end of which is connected by a link M with the piston, prefer-

ably through the medium of a pivotal connection N, which permits of a slight angular adjustment of the link during the movement of the piston.

O is a port in the casing, connecting the chamber H with the external atmosphere.

With the construction as thus far described, the tension of the spring L will normally hold the piston K in a position within the cylinder G, where the ports I are uncovered thereby permitting free communication between the passage J and the chamber F. As soon, however, as a partial vacuum is formed in the passage J by reason of its connection with the store bellows, the balance of the air pressures acting upon opposite ends of the piston will be disturbed, resulting in the inward movement of the piston by the differential pressure. This movement will close or partially close the ports I, so as to restrict the connection between the chamber F and the passage J. It is evident that by properly adjusting the resistance of the spring L in relation to the valve, any desired pressure may be exerted upon the piston to draw it outward, and only when the vacuum in the chamber F is such as to produce a differential pressure on the piston in excess of the tension of this spring, will there be any movement of the piston. On the other hand, where the vacuum is such as to produce a differential pressure in excess of the tension of the spring, the ports I will be closed or so restricted as to prevent free communication with the passage J, and as a consequence the air pressure within the chamber F is governed by the tension of the spring.

The regulator as above described is extremely delicate in its operation and will respond instantaneously to any change in pressure, so that a practically uniform pressure is maintained for the regulated air. Under practical conditions, however, the governing of the pressure alone will not result in uniform action of the pneumatics operated by the regulated air. This is for the reason that the volume and velocity of the air current are factors in the operation of the pneumatics as well as the pressure. As a consequence, where a variable restriction, such as the tempo valve, controls the air current, an adjustment of the regulator

which will secure a uniform action in one position of adjustment of said valve may not produce satisfactory results in a different position of adjustment; in other words, if the regulator is adjusted to secure a uniform speed of the motor where the tempo valve is wide open, the partial closing of said valve not only slows the motor but also changes the pressure, so that the regulator may not govern with uniformity the slower speed. To overcome this defect in the present construction of regulator, provision is made for retarding the movement of the regulating valve, so that its response to change in pressure is not as instantaneous. This permits of so adjusting the tension of the spring L that it will govern with equal uniformity where the tempo valve is wide open or nearly closed. The construction employed for this purpose is preferably as follows:

As has been stated, the casing A has formed therein a chamber H which communicates with the end of the cylinder G, and this chamber is in communication with the external atmosphere through the port O.

P is a valve for variably restricting the port O, which as shown is in the form of a slide pivoted at Q to the casing A. When the valve P is adjusted to restrict the port O, the result will be that the movement of the piston valve K, under the actuation of the differential pressure, will be retarded. Such an effect is produced for the reason that the chamber H is dependent upon the port O for communication with the external atmosphere, and when said port is restricted, the passage of air therethrough is retarded, which correspondingly retards the movement of the piston.

With the construction above described in use, the regulator is adjusted first by varying the resistance or tension of the spring L, which may be done by an adjusting screw R bearing against the spring and then by adjusting the valve P to vary the restriction of the port O. By suitable relative change of these two adjustments, the regulator may be placed in condition so that it will govern uniformly for different positions of the tempo valve B, so that whether the motor is running fast under open valve or slow under a closed valve, its speed will not vary so long as the tempo valve remains stationary.

By making the valve K cup shaped and out of thin metal, the weight is reduced to such an extent that the factor of inertia is inconsiderable in the operation of the regulator. The result of this is to obtain a more perfect regulation than would be otherwise possible.

It is obvious that the restriction of the port O causes the chamber H to act as a dash pot, whereby the speed of movement of the valve K may be regulated. The advantage of such a regulation over the ordinary regu-

lators which are actuated solely by differential pressure without speed regulation, will be at once apparent to those skilled in the art.

What I claim as my invention is:—

1. In a mechanical player for musical instruments a regulator comprising communicating chambers for the regulated and the unregulated air pressures, a valve subjected to opposed pressures directly exerted thereon, and actuated by the differential thereof to vary the extent of the opening between said chambers for the regulated and the unregulated pressures, and means for retarding the speed of movement of said valve. 70 75

2. A regulator for self-playing musical instruments comprising communicating chambers for the regulated and the unregulated air pressures, a freely movable valve subjected directly to opposed air pressures and actuated by the differential thereof to vary the extent of the opening between said chambers for the regulated and the unregulated pressures, and means for retarding the movement of air on one side of said valve to 90 95 slow the action thereof. 100

3. A regulator for self-playing musical instruments comprising communicating chambers for the regulated and the unregulated air pressures, a piston valve controlling the passage between said chambers for the regulated and the unregulated pressures, said valve being directly subjected to opposed air pressures, a tension device for actuating said valve in one direction, means for retarding the movement of air on one side of said valve to slow the action thereof, and means for relatively adjusting said tension device and said retarding means. 105 110

4. A regulator for self-playing musical instruments comprising communicating chambers for the regulated and the unregulated air pressures, a piston valve, a cylinder in which said valve travels having one end in communication with the chamber for the regulated air pressure said cylinder also communicating at a different point with the chamber for the unregulated air pressure, a tension device for actuating said piston to open communication between said chambers for the regulated and the unregulated air pressures, means for adjusting said tension device, and means for variably restricting the communication between said cylinder and the external atmosphere whereby the speed of movement of said valve is regulated. 115 120

5. A regulator for self-playing musical instruments, comprising a casing having formed therein a chamber for the unregulated air, a chamber for the regulated air, and a chamber having restricted communication with the external atmosphere a cylinder opening at opposite ends respectively to said chamber for the regulated air, and said chamber communicating with the at- 125 130

mosphere and having a port intermediate its ends communicating with the unregulated air, a piston valve for said cylinder, a tension device for actuating said piston to open communication between the regulated and unregulated air, and means for adjusting the restriction between the atmospheric air chamber and the external atmosphere whereby the speed of movement of said valve is regulated.

6. In a mechanical player for musical instruments, a regulator comprising communicating chambers for the regulated and the unregulated air pressures, a valve subjected to opposed air pressures and actuated by the differential thereof to vary the extent of the opening between said chambers for the regulated and the unregulated pressures, said valve consisting of a cup-shaped pis-

ton having thin walls, and of small mass, whereby the inertia of the valve is slight.

7. A regulator for self-playing musical instruments comprising a ported cylinder and a freely movable piston valve subjected to opposed air pressures and actuated by the differential thereof, said valve being of a cup-shape having thin walls and of small mass, a spring for actuating said valve in one direction, and a pivotal link connecting said valve and spring, and extending within the cup of the latter.

In testimony whereof I affix my signature in presence of two witnesses.
